UNITED STATES PATENT OFFICE

WILLIAM WIESE, OF CLEVELAND, OHIO

DIRIGIBLE LANDING DEVICE

Application filed March 28, 1930. Serial No. 439,779.

This invention relates to a dirigible landing device and has for its primary object to provide, in a manner as hereinafter set forth, a device of such character by means of which the landing of a dirigible may be effected with a minimum number of men.

A further object of the invention is to provide a device of the character aforesaid which includes a tiltable motor equipped with a propeller, by means of which a force may be applied to a dirigible in any direction desired in order to maneuver the same into position to be secured to a mooring mast or the like.

With the foregoing and other objects in view, the invention consists of the novel construction, combination and arrangement of parts as hereinafter more particularly described, and as illustrated in the accompanying drawings wherein is shown an embodiment of the invention, but it is to be understood that the description and drawings are to be taken as illustrative and that the invention is intended to be limited only by the scope of the claims hereunto appended.

In the accompanying drawings in which like numerals are employed to designate like parts throughout the same:

Figure 1 is a side elevation of a dirigible equipped with a landing device in accordance with this invention.

Figure 2 is an enlarged, fragmentary end elevation thereof showing the tiltable motor of the landing device disposed at a right angle to the position shown in Figure 1.

Figure 3 is an enlarged side elevation of the landing device.

Figure 4 is a section taken on the line 4—4 of Figure 2.

Referring to the drawings in detail, the numeral 1 designates the body of a dirigible which is equipped in the usual manner with a cabin 2, and a propeller 3 which is operated by means of a motor 4.

Depending from the cabin 2 are a pair of spaced supports 5, each of which is provided with a curved brace 6, the end of each brace 6 being fixedly secured to the cabin 2 and to a support 5 in spaced relation to the lower end of the latter.

Journaled in the support 5 are the outer

ends of a pair of longitudinally aligned shafts 7 and 8, the inner ends of which are fixedly secured to the housing of an auxiliary motor shown conventionally at 9, and equipped with a propeller 10. Fixedly mounted on the shaft 8, adjacent the support 5 in which it is journaled, is a disk 11 which is provided in its periphery with a plurality of spaced recesses 12. Carried by the support 5 in which the shaft 8 is journaled, and projecting over the disk 11, are a pair of spaced brackets 13 which slidably support a spring actuated plunger 14, the lower end of which is adapted to project into the recesses 12 when the latter are brought thereunder. Connected with the upper end of the plunger 14 is a bell crank 15 which is pivotally mounted on a bracket 16 disposed above the brackets 13. Extending from the bell crank 15 and into the cabin 2 is an actuating rod 17 for lifting the plunger 14 when desired.

Fixedly mounted on the shaft 7, adjacent the support 5 in which the same is journaled, is a worm gear 18 which is in mesh with a worm 19 formed on a worm shaft 20. The worm shaft 20 is journaled in a bearing 21 fixedly secured to the support 5 in which the shaft 7 is journaled, and extends into the cabin 2 with the upper end thereof in proximity to the upper end of the actuating rod 17. Above the motor 9, the supports 5 are connected together and mutually braced by means of a tie rod 29.

Leading from the cabin 2 to the motor 9 is an oil line 22 which is provided with a swivel joint 23 in spaced relation to the motor 9, and which is supported above the swivel joint 23 by means of a brace 24 which projects from the support 5 in which the shaft 7 is journaled. Also extending from the cabin 2 to the motor 9 is a gasoline line 25 which is provided with a swivel joint 26 in spaced relation to the motor 9, and which is supported above the swivel joint 26 by means of a brace 27 projecting from the support 5 in which the shaft 7 is journaled.

By operating the actuating rod 17 to release the plunger 14 from the recesses 12 in the disk 11, and by rotating the worm

shaft 20 by means of a handle member 28 at the upper end thereof, the shafts 7 and 8 may be rotated relative to the supports 5 in order to tilt the motor 9 in any direction desired. Upon releasing the actuating rod 17, the plunger 14 is forced by its controlling spring into engagement with one of the recesses 12 whereby any further rotation of the shafts 7 and 8 to tilt the motor 9 is prevented. With the motor 9 positioned in the manner illustrated in Figure 1, the rotation of the propeller 10 exerts a force on the dirigible body 1 in a directly downward direction in order to lower the dirigible toward the ground. With the motor 9 tilted at a right angle to the position shown in Figure 1, the rotation of the propeller 10 exerts a force on the dirigible in a horizontal direction.

It is thought that the many advantages of a landing device in accordance with this invention will be readily apparent, and although the preferred embodiment of the invention is as illustrated and described, it is to be understood that changes in the size, shape and arrangement of parts may be resorted to, so long as such changes fall within the scope of the invention as defined in the appended claims.

What I claim is:

1. A dirigible landing device comprising, a pair of supports adapted to be connected with the cabin of a dirigible, a pair of longitudinally aligned shafts having their outer ends journaled in said supports, a propeller equipped auxiliary motor fixedly mounted on the inner ends of said shafts, means operatively connected with one of said shafts for rotating the same to tilt the motor to selective positions, means operatively connected with the other of said shafts for locking the same against rotative movement to maintain the motor in a selected position, and a fuel line having one end discharging into the motor and having its other end adapted to extend into the cabin, said fuel line being provided with a swivel joint in spaced relation to said motor.

2. A dirigible landing device comprising, a pair of supports adapted to be connected with the cabin of a dirigible, a pair of longitudinally aligned shafts having their outer ends journaled in said supports, a propeller equipped auxiliary motor fixedly secured to the inner ends of said shafts, means operatively connected with one of said shafts for rotating the same to tilt the motor to selective positions, a disk fixedly mounted on the other of said shafts and formed in its periphery with a plurality of spaced recesses, a slidably, spring actuated plunger for selective engagement with said recesses, a bell crank having one end pivotally connected to said plunger, and an actuating rod

pivots connected to the other end of said bell crank.

In testimony whereof, I affix my signature hereto.

WILLIAM WIESE.
